UNITED STATES PATENT OFFICE

2,497,366

TALKING MACHINE NEEDLE

Amédée Nicole, Sainte-Croix, Switzerland, assignor to Hermann Thorens Societe Anonyme, Sainte-Croix, Switzerland, a firm of Switzerland

Application August 5, 1946, Serial No. 688,459
In Switzerland August 24, 1945

4 Claims. (Cl. 274—38)

1

The present invention relates to talking machine needles. Talking machines in which the needle is protected against the shocks by a device fastened to the pick-up box itself, are already known. It is an object of the present invention to provide an improved pick-up in which the protecting device is fastened to the needle itself and in order to avoid any prejudicial inertia increase of the oscillating system, this device bears on the one hand upon the needle and, on the other hand, upon the record or the sound band.

It is another object of the invention to provide an improved talking machine needle the pointed extremity of which carries a device adapted to cover the needle point at rest and to uncover the same under the action of a moving surface onto which the needle is lowered in playing position.

Other purposes and objects will be apparent from the further and more detailed description when considered in conjunction with the accompanying drawings which represent, by way of examples, several embodiments of the invention.

In the drawings each of the Figures 1 to 4 represents one of those embodiments in sectional front elevation at rest and in playing position and in side elevation at rest.

In the embodiment shown in Fig. 1, the needle 10, which may be an ordinary metal needle or a sapphire, carries on its pointed extremity, a rubber sleeve 11 having a spatula-shaped lug 12 bent in such a way that its enlarged rim comes at rest to cover the point 10' of the needle and protect it against the shocks which may occur when the pick-up suddenly falls onto the surface 13 of a record or a sound band to be played. The lug 12 is directed with respect to the surface 13 so as to be drawn by this surface ahead of the needle when this surface rotates in the direction of the arrow *f*. The point of the needle is then free and enabled to enter the sound groove of the record or of the band to be played under the weight of the pick-up to which the needle is fastened.

In the embodiment shown in Fig. 2, the lug 12 has its outer face partly covered by a lining 14 of unresilient material such as metal which is intended to preserve it from wear and tear and to render it more rigid.

In the example of Fig. 3, the lug 12 is directed with respect to the surface 13 in the opposite direction to that of the examples 1 and 2, and is provided with an aperture 15 through which the point of the needle is allowed to enter the sound groove when the surface 13 is rotated in the di-

2

rection of the arrow *f* and draws the lug forwards.

In the three of those embodiments, the rubber sleeve assumes in addition the function of an oscillation damper in that it bears on the one hand on the needle, and on the other hand upon the moving surface of the record or sound band. Its position near the point of the needle allows it to assume this function in particularly favourable condition for playing records. In the case of Fig. 3 a further advantage of the rubber sleeve results from the fact that the protecting lug sweep up the dust ahead of the point of the needle when the record rotates. The protecting sleeve may be permanently or removably fixed to the needle.

In the example of Fig. 4, the protecting device is constituted by a lug 16 of resilient metal integral with a ring 17 frictionally engaged on the needle 10. The lug 16 is shaped and sized so that its rim bent under the point of the needle lies, at rest, at a distance from this point sufficient to prevent the latter to contact the lug under the effect of a shock.

25 What I claim is:

1. In combination with a talking machine needle having its pointed end adapted to engage the sound groove of a record, a sleeve of elastic and damping material fitted on the shank of the needle above its pointed end in close contact therewith, said sleeve being formed integral with a downwardly turned resilient lug bent under the point of the needle to prevent contact of said needle point with a record until upon rotation of the record said lug is drawn from under said point, said lug being adapted to remain in contact with the record when the needle point engages the sound groove of said record thereby to dampen the oscillations of said needle.

2. In combination with a talking machine needle having its pointed end adapted to engage the sound groove of a record, a sleeve of elastic and damping material fitted on the shank of the needle above its pointed end in close contact

therewith, said sleeve being formed integral with a downwardly turned spatula-shaped lug positioned ahead of the needle in the moving direction of the record and bent under the point of the needle to prevent contact of said needle point with the record until upon rotation of the record the enlarged end portion of said lug is drawn ahead of said point, said enlarged end lug portion being adapted to remain in contact with the record when the needle point engages the

sound groove of said record, thereby to dampen the oscillations of said needle.

3. In combination with a talking machine needle having its pointed end adapted to engage the sound groove of a record, a sleeve of elastic and damping material fitted on the shank of the needle above its pointed end in close contact therewith, said sleeve being formed integral with a downwardly turned spatula-shaped resilient lug positioned behind the needle with respect to the moving direction of the record and bent under the point of the needle to prevent contact of said needle point with a record until upon rotation of the record said bent lug is drawn ahead of said point, said lug being formed with an aperture through which the point of the needle is allowed to pass to engage the sound groove when said bent lug is drawn forwards by said record, said lug being adapted to remain in contact with the moving record when the needle point engages the sound groove through said aperture, thereby to dampen the oscillations of said needle.

4. In combination with a talking machine needle having its pointed end adapted to engage the sound groove of a record, a sleeve of elastic and damping material fitted on the shank of

the needle above its pointed end in close contact therewith, said sleeve being formed integral with a downwardly turned resilient lug bent under the point of the needle to prevent contact of said needle point with a record until upon rotation of the record said lug is drawn from under said point, said lug being adapted to remain in contact with the record when the needle point engages the sound groove of said record thereby to dampen the oscillations of said needle, and a lining of rigid and wear resistant material covering the outer face of said bent portion of the lug.
